UNITED STATES PATENT OFFICE.

SIDNEY STIFFSON, OF NEW YORK, N. Y.

COMBINATION MERCHANDISE BOX AND DISPLAY RACK.

1,179,675.

Specification of Letters Patent. Patented Apr. 18, 1916.

Application filed April 2, 1915. Serial No. 18,708.

To all whom it may concern:

Be it known that I, SIDNEY STIFFSON, a citizen of the United States of America, residing at New York city, Manhattan 5 borough, county and State of New York, have invented certain new and useful Improvements in Combination Merchandise Boxes and Display Racks, of which the following is a full, clear, and exact description.

This invention relates to a combination merchandise-box and display rack, the object 10 being to provide a box or receptacle for merchandise such as neck-ties, suspenders or other articles, which are usually displayed in shop-windows or by salesman, the box being so arranged that it can be used as a display tray to exhibit or advertise the goods. By means of my improvement, a saving of 15 space is effected as well as the avoidance of handling the goods to an extent that would cause soiling or disarranging thereof. In other words, with my arrangement of box and retainer, the goods are always in a condition to be displayed without being removed from the retainer therefor which is arranged, when folded, to be completely incased by the box, the merchandise being folded with the retainer.

I will now proceed to describe my invention in detail, the essential features of which 20 will be summarized in the appended claim, reference being had to the accompanying drawing, forming part hereof, wherein:

Figure 1 is a perspective view of my improvement (the bottom of the box being broken away) arranged for displaying purposes; Fig. 2 is an enlarged sectional view of the box and folded retainer therein arranged for transportation; Fig. 3 is a front view of a modified form of retainer; and Fig. 4 is a top end view thereof.

My invention consists of a box 1 having a cover 2 removable therefrom. The goods or merchandise carried by the box are mounted upon a retainer 3 consisting of the foldably connected leaves or members 4 and 5. Each member 4 and 5 is provided with a plurality of horizontally disposed slots or openings 6 and 7 between which is located 25 a bar 8, which serves to hold the merchandise in position. In this instance the bars 8 are illustrated as retaining neck-ties 9 and 10 and suspenders 11 which are passed through the slots 6 and 7 and over the apex 30 12 of the members or leaves 4 and 5.

One of the features of my improvement consists of an extension 13 flexibly connected to the retainer-member 4 at 14. The function of the extension 13 is, when the retainer is opened for use as shown in Fig. 60 1, to provide a gutter or channel 15 in which the ends of the ties, or other articles held by the container, will lie, instead of projecting over the edge of the box. That portion of the container carrying the extension 13 will be the display portion, and, for the sake of simplicity, I will term that part of the retainer, or member 4, the front, the wall 16 of the box being the front wall. As will be seen in Fig. 1, the edge 17 of the rear retainer-member 5 rests in contact with the rear wall 18 of the box 1 when the retainer is extended for use, and the front edge of the extension 13 rests in contact with the front wall 16; hence the retainer 3 is well 70 braced when extended.

Figs. 3 and 4 illustrate another form of retainer-members, one only being shown. In this embodiment of my invention, I provide each retainer-member (the one shown being designated by 19) with a plurality of straps or bars 20 which are, at one end, pivotally secured, as at 21, to the retainer member by eyelets or otherwise. The opposite end of each bar 20 carries a socket 22 to engage or snap onto a catch 23 carried by the retainer-member 19. To mount the merchandise upon the retainer, one end of the bars 20 can be released and swung upwardly as shown by dotted lines 24 (Fig. 3) or bent 80 outwardly. After the articles have been placed upon the retainer the bars 20 can be again latched into place, thereby holding the articles carried by the retainer firmly 85 clasped.

Having now described my invention, what I claim and desire to secure by Letters Patent is:

In combination with a box, a separate removable retainer for merchandise arranged for extension for display purposes consisting of integral foldably connected members, each member being provided with a plurality of horizontally disposed slots arranged in parallelism to form retaining bars, the slots 100 extending throughout substantially the entire width of the retainer members, and the slots in one member being in alignment with the slots of the other member when the retainer members are in display position, one 105 110

of said retainer members having an integral foldable extension along its free end adapted for slidale contact with the bottom of the box and to contact with the front wall of the box to provide a gutter, all arranged so that when merchandise is placed between the respective slots, the retainer members, having such merchandise, may be folded or ex-

tended without disturbing such merchandise.

Signed at New York city, N. Y. this 1st day of April, 1915.

SIDNEY STIFFSON.
